UNITED STATES PATENT OFFICE.

HERMANN DEUTSCH, OF GROSS-LICHTERFELDE, NEAR BERLIN, GERMANY.

WRITING AND DRAWING APPARATUS.

Application filed August 2, 1922. Serial No. 579,217.

To all whom it may concern:

Be it known that I, HERMANN DEUTSCH, a citizen of Germany, residing at Gross-Lichterfelde, near Berlin, Germany, have invented certain new and useful Improvements in Writing and Drawing Apparatus, of which the following is a specification.

This invention relates to a type of writing and drawing apparatus which consists of a 10 coloured ground plate or bottom plate coated with a layer of paraffin or wax over which is spread a sheet of transparent paper upon which the writing or drawing is produced by means of a colourless style or pencil. 15 When pressure is applied to the paper by the point of the style or pencil while guiding the said point over the paper as in writing in the ordinary way the paper at the lines along which pressure is applied is 20 caused to adhere to the ground plate and writing or drawing of the colour of the ground plate then becomes visible on or through the paper. To obliterate the drawing or writing produced in this manner it 25 is only necessary to dissolve the intimate contact between the paper and the plate or to detach the paper from the ground plate, when the characters or drawing will immediately disappear. Hence the paper sheet 30 may often be used before it is renewed. The known arrangements of this kind have the disadvantage that in making the marks small furrows are produced in the paper, which also entails considerable injury to 35 the wax coating of the ground plate. Another disadvantage is that the paper is liable to be torn, so that the life of known contrivances of this kind is very limited.

The object of the present invention is to 40 overcome these disadvantages. This is accomplished by providing a transparent protective sheet above the paper sheet that is caused to adhere to the ground plate. The style, instead of being applied directly to the 45 paper is applied to the protective sheet which may consist of comparatively strong material such as celluloid, cellon or strong tracing linen. It has been found that a particularly 50 efficient kind of transparent protective sheet can be made of a pliable foil of transparent cellon which presents a very smooth writing surface, transfers to the paper sheet in a satisfactory manner the pressure applied to it by the style, and allows the characters or marks 55 to become plainly visible. When a layer of cellon is used as a protective writing sur-

face in this way, all injuries to the paper sheet are avoided and the cellon sheet itself does not suffer noticeably from the action of the style, by which the writing is produced. Another advantage obtained by using celluloid or cellon as a writing surface is that an ordinary lead pencil may be used for producing the writing or marks if no other suitable style should be at hand, 65 for the celluloid or cellon does not take the lead from the lead pencil or at any rate the graphite does not penetrate into it.

In certain cases it will be found preferable to unite the protective sheet with the 70 paper sheet, which may be done by rolling the cellon foil onto the paper sheet. The two layers, paper and protective layer, then form a single sheet so that both the paper and the protective layer can only be raised 75 or detached together from the ground plate.

The ground plate, paper sheet and also the protective layer or sheet may, if desired, be arranged in a frame, provided with suitable pockets or the like, so as to be exchangeable. 80 The arrangement can also be constructed in such a way that, to obliterate the marks, it is not necessary to raise the paper with its protective sheet. Instead of this the obliteration may be effected by placing a 85 device between the ground plate and the transparent paper by means of which the paper, which has been caused to adhere to the ground plate as a result of the writing operation, can be detached at any desired 90 part from the ground plate.

The invention is illustrated by way of example in the drawing, Fig. 1 being a plan view and Fig. 2 a section of one form of the device, while Fig. 3 is a section of a modification.

In the device shown in Figs. 1 and 2 *a* is a ground plate which may consist of card-board coated with some suitable kind of adhesive material such as wax, paraffin or the like, *b* is a thin sheet of transparent paper and *c* is a sheet of cellon or celluloid slightly thicker than the paper. The paper sheet *b* and the cellon foil *c* are joined at their upper edges *g* to the card-board plate or sheet *a*, so that both the paper and the cellon foil *c* can be lifted from the ground plate *a*.

When pressure is applied along lines of any desired shape, as in writing or drawing, on the sheet of cellon *c* by a style the said 110 lines will become visible and will disappear again immediately the sheets *b* and *c* are

lifted from the ground plate *a*. The words shown in Fig. 1 are merely to illustrate the clearness with which the device registers written matter and the ease with which the matter is made to disappear by lifting the two upper sheets as at the point C.

In the modification shown in Fig. 3 the only difference is that the sheets *b'* and *c'* are united so as to form a single sheet. This unification can be effected by rolling the layer of cellulon onto the paper sheet *b*, or the two layers may be joined by means of a colourless glue. The manner of using the modified device is similar to the mode of using the device of Figs. 1 and 2.

I claim:

1. A device of the kind described comprising a base plate with a plastic coating, a diaphanous sheet superposed on said coating, and a substantially transparent glassy-surfaced impressible sheet superposed on said diaphanous sheet, the coating and diaphanous sheet being adapted upon impressure of said sheet against said coating to adhere along the lines of impressure.

2. A device of the kind described comprising a base plate with a plastic coating, a diaphanous sheet superposed on said coating, and a substantially transparent glassy-surfaced impressible sheet superposed on said diaphanous sheet, the base plate with its

coating and the diaphanous sheet differing in color, the coating and diaphanous sheet being adapted upon impressure of said sheet against said coating to adhere along the lines of impressure.

3. A writing and drawing tablet comprising, in combination, a colored base embodying a plastic substance, a translucent impression-receiving sheet superposed on said plastic substance and adapted upon impressure to adhere to said substance along the lines of impressure, and a substantially transparent graphite-rejecting impressible tracing sheet superposed on said impression sheet.

4. A device of the kind described comprising a base plate with a plastic coating, a diaphanous sheet superposed on said coating, and a substantially transparent glassy-surfaced impressible sheet superposed on said diaphanous sheet, the contacting surfaces of said sheets being united throughout the base plate with its coating and the diaphanous sheet differing in color, the coating and diaphanous sheet being adapted upon impressure of said sheet against said coating to adhere along the lines of impressure.

In testimony whereof I affix my signature.

HERMANN DEUTSCH.
